UNITED STATES PATENT OFFICE.

FRANK VINCENT KOSATKA AND EDWARD STEPKAL, OF CICERO, ILLINOIS.

HAIRPIN.

Application filed June 17, 1922. Serial No. 569,009.

To all whom it may concern:

Be it known that we, FRANK VINCENT KOSATKA and EDWARD STEPKAL, both citizens of the United States, and residents of Cicero, in the county of Cook and State of Illinois, have invented a new and useful Improvement in Hairpins, of which the following is a full, clear, and exact description.

Our invention relates to improvements in hair pins, and it consists in the combinations, constructions, and arrangements herein described and claimed.

An object of our invention is to provide a hair pin which automatically locks itself in the hair.

A further object of our invention is to provide a hair pin which is simple in construction and which is durable and efficient for the purpose intended.

Other objects and advantages will appear in the following specification, and the novel features of the invention will be particularly pointed out in the appended claim.

Our invention is illustrated in the accompanying drawings, forming part of this application, in which—

Figure 1 is a front elevation of the device,

Figure 2 is a side elevation of the device, showing the hair pin in collapsed position, and

Figure 3 is a side elevation of the device.

Loss of hair pins is due to the fact that the pin is not clamped in position in the hair and therefore readily slides out. In the present device, the wire 1 is curved in such a manner that it will automatically lock itself in place after once being disposed in the hair. In Figure 1 we have shown the wire 1 as being provided with a loop portion 2, the sides 3 of the wire being again fashioned into a loop 4, and into parallel end portions 5. The sides 3 are spaced from each other, as clearly shown in Figure 3, so as to permit the hair to readily enter therebetween. The wire 1 is more or less flexible so as to permit the loop 2 to be compressed (see Figure 2) and thus move the ends 5 toward each other.

From the foregoing description of the various parts of the device, the operation thereof may be readily understood. When

inserting the hair pin into the hair, the sides 3 are moved toward each other, as shown in Figure 2. The pin is now inserted in the hair, the pin being disposed in a vertical plane as it enters the hair to cause the ends 5 to receive the hair therebetween. By moving the pin into the hair, the recess 6, formed by the spaced apart sides 3, receives the hair. It is obvious that the sides 3 are swung slightly outwardly as the hair is forced into the recess 6. When the hair reaches the loop portions 2 and 4, it tends to turn the hair pin into a position at right angles to a position from which it enters. As soon as the pin is released, it will instantly swing through an arc of 90° and lie flat against the head. The hair now extends through the loops 2 and 4 and prevents the pin from being removed until it is again turned through an arc of 90°. From this operation, it will be apparent that the pin may be readily inserted in the hair of the wearer and be automatically locked in place when released, whereby the pin cannot drop out. The arrangement of the loops 2 and 4, and the spacing of the sides 3 from each other, provides a simple means by which the pin is effectively locked in place in the hair. It is obvious that the pin is invisible when once inserted in the hair as is the ordinary hair pin. The device can be manufactured cheaply and at slight expense.

We claim:

A hair pin comprising a wire bent back upon itself to provide hair engaging members, each member being provided with undulations or corrugations throughout a part of its length and being provided with a straight portion adjacent to its end, the undulations of one member lying in one plane, the planes of each member being spaced from each other, thereby permitting hair to be received between said members, the hair lying in a plane parallel to the planes of said members, the undulations of both members co-operating to form hair receiving loops, the hair when received in the loops extending at right angles to the planes of said members, one of the hair receiving loops being the closed end of the hair pin.

FRANK VINCENT KOSATKA.
EDWARD STEPKAL.
